UNITED STATES PATENT OFFICE.

JOHN M. HOLCHIN, OF CLEVELAND, OHIO.

HAIR-DRYING BRUSH.

Application filed September 4, 1924. Serial No. 735,883.

To all whom it may concern:

Be it known that I, JOHN M. HOLCHIN, a citizen of the United States, residing at Cleveland, in the county of Cuyahoga and 5 State of Ohio, have invented certain new and useful Improvements in Hair-Drying Brushes, of which the following is a specification.

This invention relates to improvements in 10 hair drying brushes having for an object the provision of a structure composed of a minimum number of stamped or drawn sheet metal parts which may be comparatively inexpensively made up and easily assembled.

Another object is to provide a brush of 15 this character in which the hollow hair drying teeth are drawn from a sheet of metal and are yieldably carried by the brush back.

It is likewise an object to provide a brush 20 of this character including a base plate from which the hair drying teeth are drawn, and a stamped cover plate designed to house a heating element.

Other objects will be in part obvious and 25 in part pointed out hereinafter.

In order that the invention and its mode 30 of operation may be readily understood by persons skilled in the art, I have in the accompanying illustrative drawings, and in 35 the following detailed description based thereon set out one possible embodiment of the same.

Figure 1 is a perspective view of the complete brush;

Figure 2 is a vertical longitudinal sectional view thereof;

Figure 3 is a fragmentary bottom plan view of the brush;

Figure 4 is an enlarged longitudinal section of the forward end of the brush as 40 shown in Figure 2, showing the tooth formation and connection between the tooth carrying plate and the top or cover plate;

Figure 5 is a detail sectional view showing 45 a modification wherein the teeth are separately formed and retained in the bottom plate by means of a retaining sheet of metal;

Figure 6 is a top plan view of the brush;

Figure 7 is an edge view, parts being 50 shown in section, this being a further modification of the brush; and

Figure 8 is a detail sectional view of the form shown in Figure 7.

Having more particular reference to the 55 drawings throughout which similar characters of reference designate similar parts this

improved hair drying brush may be stated as comprising in its preferred form a sectional back including a base plate 10 from which hollow teeth 11 are drawn, a heating element 12 arranged above the hollow teeth, a sheet metal retaining plate 13 designed to retain the heating element in proper relative position, a hollow top shell or housing 14 having its edge attached to 60 the periphery of the base plate 10, a packing or heat insulating material 15 arranged between the housing 14 and the retaining plate 13, and a handle H connected to the housing 14 and carrying a current 65 conducting cord C.

In the formation of the preferred form of this invention I take a strip of sheet brass, aluminum or the like metal from which I draw the teeth 11 as shown in Figures 2 and 4, this drawing operation assuring a smooth unbroken surface over the entire area which will come in contact with the hair and scalp of the person using the brush. This drawing operation by means 75 of which the teeth are formed obviously necessitates a number of successive operations before the teeth assume the configuration shown in Figure 2, that is, each successive operation further elongates the teeth 80 until they are shaped as shown in this figure.

A heating element 12 is arranged upon this base or tooth carrying plate 10 and preferably consists of a heating wire covered with asbestos. As indicated in Figure 3 this 90 heating element is arranged upon the base plate so as to cover such an area as will assure uniform heating of the set of hollow teeth. This heating element must be held in proper relative position with respect to 95 the tooth carrying plate 10 and in order to accomplish this I arrange thereabove a retaining plate 13 formed of sheet metal and turn its periphery downwardly into contact with the upper face of the tooth carrying 100 plate near its edge.

A hollow top shell or housing 14 is arranged above the heating element retaining plate 13 and as shown in Figure 4, has a peripheral flange 16 snugly contacting with 105 the peripheral portion of the retaining plate 13, these associated portions being positively held together through turning upwardly and thereover the flange portion 17 of the tooth carrying plate 10. Obviously 110 this connection provides a reliable rigid construction such as will insure retention of

the heating element in proper position. The arrangement of the hollow housing 14 in spaced relation with respect to the retaining plate 13, provides a chamber in which a heat insulating material 15 may be packed, the function of which is quite well known.

As shown in Figure 2, this housing 14 is provided near one end with an opening 18 through which an electric current conducting cord C enters for connection to the heating element. Riveted or otherwise attached to this housing 14 over the opening 18 is a hollow sleeve or neck 19 whose outer end is tightly fitted into one end of a longitudinal passage-way through a wooden handle H. A metal ferrule 20 is carried by the inner end of the handle H and obviously is designed to prevent splitting of the handle portion.

It is understood that in using this brush the current is turned on and the heating element 12 gradually heats the hollow teeth 11, the brush then being used in the same manner as an ordinary brush or comb. It is obvious that the heated teeth being drawn through the hair after shampooing or otherwise treating the hair will quickly and satisfactorily effect the drying thereof.

In Figure 5, I show a modified form which includes in place of the integral formation of the teeth and base plate, a base plate 21 in which is formed a set of spaced openings 22, the metal forming the walls of the openings being turned downwardly to form short necks 23.

Each of the drawn hollow teeth 24 is substantially cone shaped, the base portion 25 being flared outwardly for contact with the inner or upper face of the base plate 21 as shown in Figure 5. In order to retain these outwardly flared portions in snug contact with the base plate 21, I provide a tooth retaining plate 26 which tightly engages all of the teeth 24 and is held in such position by means of a heating element retaining plate 27 whose edge is turned downwardly into contact with the tooth retaining plate 26 as clearly shown in Figure 5. A heating element 28 is disposed between these last two named plates and may be arranged in any preferred manner. A hollow housing or shell 29 is arranged above a heating element retaining plate and includes a heat insulating material such as asbestos, and has its edge or periphery extended downwardly over the periphery of the tooth and heating element retaining plates and held in such position through turning upwardly a flange portion 30 of the tooth carrying plate 21.

In a further modification as shown in Figures 6, 7 and 8 I employ a base plate 31 having short hollow necks or sleeves 32 drawn therefrom and provided with inwardly turned shoulders or flanges 33 at the lower ends as illustrated in the detail sec-

tional view. Hollow elongated teeth 34, substantially cone shaped, have their base portions flared outwardly to engage over the shoulders 33 of the necks and sleeves 32, thereby providing a loose connection between said teeth and necks. Obviously the teeth 34 are normally positioned as shown in Figures 7 and 8 and in order to assure such positioning under normal conditions a coil expansion spring 35 is arranged in the sleeve or neck 32, having one end bearing against the flared portion of the adjacent tooth 34, while its other end bears against a spring retaining plate 36 which is of sufficient area to cover the entire sleeve or neck carrying base plate 31. A heating element retaining plate 37 is arranged above the spring retaining plate 36 and in addition to holding the heating element 38 in position, serves to prevent shifting of the spring retaining plate 36 through provision of the downwardly turned edge portion 39 as illustrated. A hollow shell or housing 40 is arranged above the heretofore described elements and encloses a heat insulating material 41, and further serves to form a rigid structure through connection to the base plate 31 as shown in Figure 8. This connection consists in turning upwardly and over the edge of the housing or shell 40 a flange 42 carried by the base plate 31.

A handle H' is connected to the shell 40 by means of a hollow neck 43 whose inner end is flared and riveted or otherwise secured to the shell. The outer end of this neck 43 is tightly forced into an opening which extends throughout the length of the handle H' for the reception of a current conducting cord (not shown). A ferrule 44 is secured to the inner end portion of the handle H' for obvious reasons.

The construction of this brush with teeth mounted as just described will provide yieldability of the entire set of teeth and consequently prevent injury to the scalp of the user as is quite obvious. It is understood that in drying hair the teeth of the brush often encounter tangles or irregularities in the head formation and due to the longitudinal and lateral yieldability of the teeth this condition will be properly cared for.

In the form shown in Figures 1 to 4 inclusive the teeth are drawn from a single sheet of thin metal such as brass or aluminum and due to this formation the expense of manufacture is considerably reduced. The fact that practically the entire structure is either stamped or drawn from light sheet metal provides for comparatively inexpensive manufacture and the small number of parts obviously greatly facilitates assembly of the structure.

Certain changes in the minor details of structure may be resorted to and such of

these changes as may fall within the scope of the appended claims I consider within the spirit of my invention.

I claim:

5 1. A hair drying brush including a sectional hollow back, a set of hollow teeth carried by the back and having communication with the interior, an electric heating element arranged in the back, and a handle 10 attached to the back.

15 2. A hair drying brush including a sectional hollow back, a set of hollow teeth carried by the back and having direct communication with the interior, an electric heating element arranged in the back over the inner ends of the teeth, a heating element retaining plate snugly contacting with the heating element and having its periphery clamped between and at the point of 20 inter-connection of the sectional back, and a handle attached to the back.

25 3. A hair drying brush including a sectional hollow back, said back comprising a hollow top shell having an opening at one end, a hollow handle arranged over the opening, a base section having connection at its periphery to the top shell, a set of hollow drawn metal teeth carried by the base section, and a heating element arranged in the back over the inner ends of the teeth.

30 4. A hair drying brush formed from sheet metal and comprising a two-part

back, a handle attached to the back, one part of said back having a set of openings, a set of hollow teeth having flared inner ends to take over the walls about the openings, means for retaining the flared ends and walls in snug relative contact, and an electric heating element arranged in the 40 back.

5. A hair drying brush formed from sheet metal and comprising a two-part back, a handle attached to the back, one part of said back having a set of openings, a set of 45 hollow teeth having flared inner ends to take over the walls about the openings, a retaining plate arranged over the flared ends of the teeth, an electric heating element over the retaining plate and means for 50 holding the heating element in proper relative position.

6. A hair drying brush formed from sheet metal and comprising a two-part back, a handle attached to the back, one part of 55 said back having a set of openings, outwardly turned flanges formed about the openings, a set of hollow teeth having outwardly flared inner ends fitting over said flanges and contacting with the inner face 60 of said one part, a retaining plate snugly contacting with the flared ends of the hollow teeth, and an electric heating element arranged upon said plate.

In testimony whereof I affix my signature.
JOHN M. HOLCHIN.
